[57] CLAIM

The ornamental design for a handheld interrogator, as shown and described.

DESCRIPTION

FIG. 1 is a perspective view of the handheld interrogator showing our new design;

FIG. 2 is a front elevational view thereof, the rear view is a mirror image;

FIG. 3 is a top plan view thereof;

FIG. 4 is a bottom elevational view thereof;

FIG. 5 is a right side elevational view thereof; and,

FIG. 6 is a left side elevational view thereof.

The broken line drawing in all figure views is for illustrative purposes only, and forms no part of the claimed design.
